UNITED STATES PATENT OFFICE.

JOHN EMERY HARRIMAN, JR., OF BROOKLINE, MASSACHUSETTS.

AEROMOBILE.

1,161,664.

Specification of Letters Patent. Patented Nov. 23, 1915.

Application filed February 19, 1910. Serial No. 544,832.

To all whom it may concern:

Be it known that I, JOHN E. HARRIMAN, Jr., of Brookline, in the county of Norfolk and State of Massachusetts, have invented certain new and useful Improvements in Aeromobiles, of which the following is a specification.

This invention relates to mechanical flying apparatus, and has for its object to provide an improved machine of great flexibility as to its modes of use and capable of more extended and better control, and greater flexibility and range of adjustment than any of the apparatus or devices of this character hitherto known.

My object also has been to provide a machine capable of carrying one or more persons, and capable of control and guidance from different points to insure safety in case of accident to or incapacity of the person normally acting as the driver or engineer of the machine.

Still another object has been to construct a machine of a number of units capable of indefinite extension and multiplication, and of separation for independent use, or for assembling in relatively different positions, as regards the direction of normal movement of the apparatus.

Still another object has been to make provision for adjusting the wings or planes with respect to the vertical, for securing balance in soaring, and for experimentation.

In short the ends which I have had in view in designing the present invention have been, as before stated, to provide perfect flexibility between the various main parts of the machine, whereby to secure complete and sure control, stability or balance in the air, and wide range of adjustments for purposes of study and experiment, while at the same time insuring sufficient rigidity and strength in the several units or main parts of the machine.

In carrying my invention into effect I have devised a combination including a central longitudinal member or backbone, with which all of the other parts are connected, a flexible and adjustable aeroplane construction, consisting of pivotally connected wings, each of which may be a monoplane or superposed multiplanes, a rigid aeroplane adjustable in all directions with respect to the winged planes and the backbone, and a propelling engine, together with complete means of control. In connection with the

working out of the invention in practical form I have applied the truss principle to the supporting planes and have developed new types of truss as applied to the wings and planes of a flying machine.

For convenience of description, and as furnishing appropriate and descriptive designations to the parts of the machine, I prefer to call the machine as a whole an aeromobile, the part including the pivotally mounted and oscillable wings the winged aeroplane, and the construction, including the relatively rigidly connected planes, the aerocar.

In the drawings I have illustrated an apparatus embodying the principles of my invention in the form which at the present time I consider the best and most practical.

In these drawings, Figure 1 represents in side elevation the aeromobile as a whole. Fig. 2 is a plan view of the same. Fig. 3 is a front elevation of the winged aeroplane portion of the aeromobile showing the wings extended. Fig. 4 is a view of the same part of the machine, showing the wings in a different position, such as they may occupy for soaring. Fig. 5 is a front elevation of the part which I term the aerocar, showing the backbone of the machine in section. Fig. 6 is an elevation showing the central part of Fig. 3, illustrating the details of such figure more clearly. Fig. 7 is an elevation showing the central part of Fig. 4. Fig. 8 is an elevation of the part shown in Fig. 7 as seen from the right of such figure, the right-hand winged plane being broken away for clearness. Fig. 9 is a plan view of Fig. 6. Fig. 10 is an elevation of the steering propeller and controlling means therefor, representing a modification of the construction shown in Fig. 1. Figs. 11 to 16 represent a modification showing the application of the monoplane principle to the aeroplane and showing respectively an under plan view, a side elevation, a front elevation, a rear elevation, a front elevation of the aerocar detailed, and a detail sectional view on the line 16—16 of Fig. 13.

The same reference characters indicate the same parts in all the figures.

In the drawings the numeral 1 represents a shaft which extends longitudinally of the fore-and-aft center line of the machine and constitutes the backbone to which all parts of the machine are connected and by which they are tied together. This shaft is repre-

sented in dotted lines in Fig. 1, being hidden by the inclosing tubular casing 2 which constitutes a tubular frame or backbone. Upon this backbone is mounted the winged ⁵ aeroplane, consisting preferably of two wings which are pivotally mounted upon the shaft or rather the casing surrounding the shaft. These wings are best shown in Figs. 3 and 4, and each is represented as consisting of two planes, 3 and 4, the former of which is superposed above the latter. I desire to note here that I am not necessarily limited to two superposed planes for the wing structure, but reserve the right to use ¹⁰ more than two planes, or to make each wing as a monoplane. The truss construction which I have devised for these wings lends itself to the support of any number of planes, whether one or more. Each of the ¹⁵ wing planes extends across and is supported by two curved trusses, the forward or anterior of which consists of a longitudinal member 5, which extends transversely of the fore-and-aft line of the machine, but ²⁰ longitudinally (that is in the direction of the greatest dimension) of the wing, a strut or compression member 6 and a chord or tension member 7 passing from the opposite ends of the longitudinal member 5 beneath ²⁵ the end of the strut. This truss construction gives all necessary rigidity to the wing ³⁰ resistant to the upwardly acting air pressure. For structural reasons, and in order to distribute the stresses and increase the rigidity ³⁵ of the truss I preferably provide more than one strut, the present design showing two struts 8 and 9 respectively in addition to the strut 6, all of these struts being connected together at a common point and radiating ⁴⁰ therefrom toward the longitudinal member 5. It is to be understood, of course, that any number of struts may be employed.

In a like manner the posterior portion of the wing is supported by a similar truss, ⁴⁵ of which only the longitudinal member 10 is shown in Fig. 2, it being understood, however, that such posterior truss is the same in all respects as the anterior one above described. Likewise the under wing 4 is ⁵⁰ supported by forward and rear truss frames, consisting of longitudinals 11 and struts, which are conveniently the same struts previously described. That is, the longitudinals 5 and 11 are both connected to the struts 6, 8 and 9 and are braced thereby, while the chord 7 is connected to the outer end of the member 11, as well as the member 5. Conveniently the trusses 5 and 11 ⁵⁵ converge and are connected together at their inner ends, as shown in the drawings, both being attached to a block 12, although this construction is not absolutely necessary, and they may be parallel throughout their entire length, if desired. Ribs 13, as shown in ⁶⁰ Figs. 1 and 2, extend in a fore-and-aft di-

rection between the longitudinal truss members 5 and 10, and between the lower longitudinal anterior and posterior truss members 11, for supporting the fabric which supplies the wing surfaces. If desired, ⁷⁰ these ribs may be extended beyond the rear trusses, as shown in Figs. 1 and 2, and connected to a rod 14, to which the rear edge of the fabric is attached. In addition diagonal tension members 15 are arranged in a vertical plane in the panels between the struts and outer chord to stiffen the structure in a well-understood manner; while diagonal tension members 16 extend between the anterior and posterior trusses, as shown in Fig. 2. ⁷⁵ I have illustrated the wings as being convex on their upper surfaces, both in the direction of their length and in a fore-and-aft direction. To secure the fore-and-aft curvature the ribs 13 are somewhat bowed at their forward ends, having a gradually increasing amount of curvature from the tips of the wings inward. Likewise the inner extremities of the wing coverings are shown as being bent sharply downward, being connected to strips 5^a and 11^a, which are curved so as to lie at their ends against the strut 8. This curvature provides pockets at the forward edges of the wings and at their inner extremities, to obtain additional ⁸⁵ sustaining and forward propelling force from the air. This construction, however, may be modified in any desired degree and the inner extremities of the fabric wing coverings caused to follow the lines of the truss ⁹⁰ members absolutely, if desired.

The description above given of one wing applies equally to both, and consequently the same reference characters are applied to both wings, as shown in Figs. 3 and 4. ¹⁰⁵

It will be noted that the longitudinal members of the trusses cross the fore-and-aft axis of the machine and are connected to blocks 17, which are pivoted upon the shaft casing 2. The extreme ends of the wing frames are connected by links 18 with a fore-and-aft rod 19, which extends from the forward pair of links to the rear pair, that is, to the links which are connected with the posterior truss frames of the wings. The ¹¹⁰ forward end of the rod 19 slides in a slot 20, which is formed in a bar 21 extending downwardly from the shaft casing and connected thereto. The rear end of this rod is connected to a bar 22 which has a slot or ¹¹⁵ passage 23 (Fig. 6) to receive the shaft and casing, and is capable of moving up and down thereon.

The ends of the frames of each wing are connected by a fore-and-aft rod 24, on which ¹²⁰ the operator may stand, as indicated in the drawings, so as to depress these ends and thereby elevate the wings in the manner illustrated in Figs. 4 and 7.

Between and above the wings is a para- ¹²⁵

chute frame consisting of forward-and-aft bowed members 25 and 26, pivotally connected to the wing frames, preferably to the upper ends of the struts 8, as shown at 27 5 and 28, and pivoted together at their upper ends by means of a rod 29. Over the bowed frames is stretched a covering 30, whereby this part of the apparatus constitutes a 10 parachute which resists and retards descent, or in other words, exerts a relatively upward pressure when the machine is descending. A part or all of this covering, particularly at the sides of the parachute frame, may be transparent, and may be planes or sheets 15 of such a material as celluloid or other material suitably treated to insure transparency. This transparent feature is important, as the operator is stationed between the planes or vanes, and it is necessary that 20 his view to either side should not be materially obstructed. These upright planes constitute vertical vanes or rudders which tend to direct or guide the aeroplane in a uniform straight line of travel, as will be 25 readily understood. At the sides of the parachute frame are rods or bars 31, 32, which enable the operator to shift his weight and serve for controlling and guiding the machine as hereinafter described. A seat 33 is 30 provided for the operator, and is hinged to the bar 22, which as previously described, is attached to the rear end of the rod 19. The seat may be swung back on its hinges out of the way of the operator when the 35 latter is standing on the rods 24 or the platform 34. The platform is hung from the central shaft.

It will be understood from the foregoing that the operator is enabled to shift his 40 weight from one part to another of the aeromobile, and particularly to apply his weight to different portions of the wings. Thus by standing on the rods 24 the operator's weight is exclusively applied to the 45 extreme ends of the wing frames in such a manner as to tend to elevate the wings, as shown in Figs. 4 and 7, the wing frames crossing each other so that depression of the inner ends thereof tends to lift their outer 50 portions. On the other hand when the operator's weight is transferred to his hands grasping the rods 31 and 32, the application of such weight to the wings is transferred to the points 27 and 28 of connection of the 55 parachute yoke to the wing frames, which points are on the opposite sides of the pivotal axis of the wings from the inner ends of the wing frames. This transfer of weight tends to lower the wings into the position 60 shown in Figs. 1, 3, and 6. Then, when the operator stands on the platform 34, his weight is hung directly from the shaft or backbone of the machine, and when he sits upon the seat 33 his weight is supported by 65 the bar 22 and therefore hung from the two

pairs of links 18. When the machine is in the air the upward pressure of the air, acting in opposition to the pull of gravity at the center of gravity of the machine, tends to raise the wings. This tendency is resisted 70 and to a greater or less extent counteracted by a spring 35, which connects the wings with each other below their pivotal support. There are also springs 36 and 37 which extend between the bar or pin 19 and the platform 34 which act to the same purpose. These springs are or may be provided with any desired adjusting means, so that their tension is adjusted to the required amount according to circumstances. By proper 75 adjustments of these springs the balance may be made so even that a slight shifting of the weight from the bars 24 to the hand rods 31 and 32 will suffice to set the wings at any desired angle. Thereby the operator 80 may make continual shifts in the position of his wings if desired, in order to secure balance and stability in shifting aerial currents, or he may hold the wings steadily at any particular angle which experiment determines to be most suitable for his purposes 85 in soaring or gliding and in different degrees and conditions of atmospheric disturbance. By resting his weight to a greater or less degree on the seat and platform 33 90 also, adjustment of the wings and maintenance of the latter in any adjustment may be further controlled. I find it desirable and useful, if not absolutely necessary, to provide power means for adjusting the 95 wings, which may be used in conjunction with or independently of the shifting of the operator's weight, the power means consisting of a piston rod 38 connected at its lower end to the rod 19 and having at its upper 100 end a piston, which is contained in a cylinder 39. The latter enters an air-compressor chamber 40 and is adapted to receive compressed air or other motive fluids on opposite sides of the piston under the control of 105 the foot levers 41 and 42. By suitably operating the pedals of such levers the wings may be raised or lowered automatically 110 without requiring expenditure of energy on the part of the operator. Means for retaining the wings in any of their adjustments may be provided, as for instance, by an additional lever 43, having a brake member or pawl 44 engaging the piston rod 38 and bearing frictionally against the same 115 or engaging teeth or recesses thereof.

For propulsion I employ a propeller 45 mounted preferably on the forward end of the shaft 1. The propeller and shaft are rotated by a motor 46 which may be of any 120 of the approved types now used, but is preferably a rotary engine of the type developed under my direction and exemplified in the pending applications of F. C. Morton, Serial No. 273,904 and No. 462,972, developing 125

power from the combustion of an explosive charge or, under some circumstances, from the consumption of steam. The motor illustrated here consists of four units, two of which may be generators and the other two air-compressors or the like. I desire it to be understood, however, that I do not limit myself to any particular type of engine, but reserve the right to use any kind whatever, whether of the rotary or the reciprocating type, and working on any principle, that is through development of heat internally by combustion of fuel in its working chamber or chambers, or by an externally provided working fluid, or an electric motor. For my purpose, however, I consider it preferable to employ such a form of engine or connect the same in such manner to the shaft as to avoid the necessity of forming cranks in the shaft, as the presence of cranks increases the difficulty of taking the machine apart and reassembling. It is not impossible, however, to use a crank, and the shaft may if necessary be provided with a crank shaft section. Control levers for the engine are represented at 47 and are shown merely to illustrate the position in which said levers may be placed for convenient access by the operator. As the essence of my invention relates to the combination of the aeromobile as a whole and to the parts thereof herein more particularly described and claimed, without being dependent upon any particular type of motor or mode of control thereof, I have not deemed it necessary to illustrate the same with any greater degree of particularity than merely to indicate the presence of a motor and of controlling means therefor.

On the backbone of the machine, which, as before stated, consists of the shaft 1 and its casing 2, I mount an additional aeroplane which for purposes of description I term an aerocar. This aerocar is constructed primarily of a U-shaped frame 48, to which are connected the upper and lower superposed planes 49 and 50. The upper plane consists of forward and rear rods 51 and 52, extending transversely of the machine as a whole, but longitudinally of the greatest dimension of the plane, for which reason I term them longitudinal rods, to which the forward and rear edges of the cloth coverings are attached, and ribs 53 in the usual manner, while the lower plane consists of the longitudinal rods or bars 54 and 55 and ribs 56. These planes are hung from the U-shaped frame 48 between the upper and lower extremities thereof, being suspended by tension members 58, 59 and 60, which extend from the end of each leg of the frame to the frame members of the wings, and are preferably wire. The planes are further stiffened and held in place by chords 61 and 62, connected to the U-shaped frame below the upper plane, and chords 63, con-

necting the lower plane with brackets 64 which are detachably connected to the bottom of the U-shaped frame and extend below the same. In addition further vertical and diagonal members are carried between the planes and from the lower plane to the frame 48 between the side members thereof, thus stiffening and bracing the planes in all directions. It will be noted that the only mode of connection between the upper and lower planes 49 and 50 is by means of the vertical tension members 65 and the diagonal members 66. There are no rigid struts between the planes to hold them at a fixed distance apart, such as are necessary in the bi-plane flying machines hitherto produced, but the planes are located and held at the proper distance apart wholly by the rigid U-shaped frame with which they are connected as above described.

The means for supporting the aerocar and connecting it to the backbone of the aeromobile consists of a collar 67 which slides upon the shaft casing 2 and is adapted to be secured in any position thereof by a set screw 68. Upon the top of the collar is swiveled a bearing 69, said bearing being thus enabled to swing about a vertical axis, and through the bearing is passed a rod 70 which also passes through the side members or legs of the frame 48 and supports the weight of the latter. The rod 70 can turn in the bearing 69 about its own axis, and thus the aerocar as a whole is enabled to turn about the horizontal axis of the rod 70 and the vertical axis of the swivel connection of the bearing 69 with the collar 67. These movements of the aerocar serve for guiding the aeromobile as a whole up or down and to the right or left. The oscillating movement about the axis of the rod 70, of course, governs the elevation of the aeromobile in an obvious and well-known way, while the oscillation about the vertical axis of the bearing 69 serves to guide the machine to the right or left by virtue of the rudder vanes which are indicated by the heavily shaded lines 71 in Fig. 5. These vanes may be thin plates, if desired, or sheets of cloth, carried by the side members of the frame 48 and extending in vertical planes parallel to the fore-and-aft axis of the machine. The outline of the rudder vanes is indicated by the wires or lines 72, 73, 74, 75, 76, and 77 in Fig. 1. Where the vanes are made of cloth they are fastened to and supported by the wires last indicated at their edges. The vanes may be made in two or three separate parts, in order that their extreme upper and lower portions may extend respectively above and below the superposed supporting planes 49 and 50. These vanes may also be made of transparent material, such for instance as celluloid, in order that the operator or passenger seated in the chair 112

hereinafter described may not have his view to either side obstructed. It will be noted by a reference to the drawings that the head of the person seated in this chair will be between the upright planes.

The aerocar is capable of still an additional movement, that is, a careening movement about the axis of the shaft 1. For this purpose the rear portion of the casing 2 is made and mounted so as to be capable of swinging about the shaft 1 and connected to said casing is a lever 78. This lever when oscillated transversely of the shaft turns the casing 2 and with it the aerocar, tilting up one end of the planes thereof and depressing the opposite end. By this means the aerocar may be utilized to steady the machine and overcome the tendency to overturn which may be occasioned by change in the direction of travel or by air currents striking the forward wing planes unequally.

I utilize the lever 78 also for tilting the aerocar and the hand rods 31 and 32 for swinging the aerocar to the left or right. For tilting the aerocar and thereby elevating or depressing the axis of the machine, I provide wires 79, which extend from a cross piece 80 (Fig. 9) on the lever 78 to eyes 81 on the brackets 64, and wires 82 which extend from the upper ends of the side members of the U-shaped frame 48 forward, around guide pulleys 83 and thence to the same cross piece 80. As will be obvious, oscillating the lever 78 forward or back will reversely oscillate the planes of the aerocar, whereby a movement of the lever forwardly will cause the machine to descend and a movement thereof to the rear will cause it to rise. It should be noted that the lever 78 is pivotally connected to the shaft casing 2 and is thus enabled to swing in a fore-and-aft vertical plane. Preferably, in addition to the controlling wires, I provide springs 84 and 85, which extend from the top and bottom of the U-shaped frame to a fitting at the rear end of the shaft casing and assist in retaining the aerocar in its position of equilibrium.

For swinging the aerocar and thereby steering the machine to the right or left, I provide wires 86, 87 which extend from opposite ends of the aerocar, and preferably the opposite ends of the bar 70 to the hand rods 31, 32 on respectively opposite sides of the longitudinal axis of the machine. A wire 88 is connected at its ends to both hand rods and passes around a pulley 89. Thereby with either rod an equal and opposite movement is imparted to the other rod and the aerocar is at the same time swung in the desired direction. For instance, supposing it to be desired to deflect the course of the aeromobile to the right, a backward pull is given upon the right-hand rod 32. This causes the left-hand rod to be moved for-

ward, a pull to be given to the wire 86 and the aerocar to be swung in the manner of a rudder for steering. Thus deflection to right or left may be accomplished by moving either or both of the rods 31 and 32. Springs 90 and 91 extend from the sides of the aerocar to the rear end of the shaft casing and complete the circuit of the wires, and also tend to hold the car in its position of equilibrium. I also provide on the end of the shaft for purposes both of auxiliary propulsion and auxiliary control and guidance, a secondary or auxiliary propeller 93 which is mounted on the end of the shaft 1 by means of a ball and socket joint or universal joint 94. The propeller is enabled to tilt about an axis transverse to the shaft owing to the pin and slot connection which it has with the ball 94, there being a pin 95 passing through the ball into a curved slot 85 in the hub of the propeller. The pin transmits rotation of the shaft to the propeller while permitting such oscillation as has been described. The oscillation or angular displacement of the propeller is accomplished by the control lever 78 previously described through wires 97, 98 which are connected with a lever 99 pivoted to the shaft casing, said lever carrying anti-friction rolls 100 bearing against the hub of the propeller. When the lever is tilted forward or back in a vertical plane, the propeller 93 is so tilted as to exert its thrust respectively upwardly or downwardly at a slight angle, so as to tend to raise or lower the machine and thus reinforce and emphasize the similar tendency of the aerocar. If, however, it is desired to use the propeller for steering to the right or left, the lever 78 is swung laterally, whereby the lever 99 is also moved with the casing in the same manner and to the same extent, and upon the lever 78 then being moved forward or back, the line of thrust of the propeller is deflected to right or left.

In Fig. 10 I have illustrated a modification in the mode of controlling the propeller. In this figure the propeller 93 is mounted upon the shaft 1 as previously described, and an endwise movable casing 2 is mounted upon the shaft. Instead, however, of having a lever 99 pivoted to the shaft, the device which tilts the propeller is a sleeve 101 secured to the casing and having either a single wheel 102 or two wheels 102 and 103 on opposite sides of its axis, of which the former extends farther to the rear than the latter and normally bears against the hub of the propeller when the latter is perpendicular to the shaft. Upon moving the casing to the rear by means of the lever 78, the sleeve 101 is also moved rearwardly and the wheel 102 caused to bear on the propeller, thereby tilting the same, as indicated in Fig. 10, the limit of tilting being deter-

mined by the position and size of the wheel 103. Likewise, by oscillating the casing 2 about its axis, the propeller may be caused to exert a thrust either to right or left. Although I have shown the propeller as connected with the shaft by a ball and socket joint, I desire to observe that this is not the only possible, nor necessarily the most preferable, form of connection, since any other convenient and suitable form of universal joint may be employed.

Upon referring to Fig. 1, it will be noted that I have provided traction wheels 104 and 105, upon which the aeromobile may run when being supported and in alighting. The wheel 104 is carried in a frame 106 swiveled upon the lower end of the bar 21, which, as before stated, depends from and is secured to the forward part of the shaft casing. It may be here observed that the shaft casing is made in two parts, the forward part 2^a of which is secured to the motor casing, and is not independently oscillable. The other traction wheel 105 is pivoted upon an axle extending between the brackets 64 which are secured to the frame 48 of the aerocar. In addition the wings have supporting wheels 107 which bear upon the ground in case the wings are depressed, as shown in Fig. 3, before the machine rises from the ground.

In putting the apparatus into flight it is, of course, caused to run along the ground on its supporting wheels, the wings of the aeroplane portion being raised. When sufficient momentum has been acquired, the wings are depressed, and this will have the effect of raising the car, either owing to their downward pressure upon the air, or, in case this is not sufficient, by their wheels 107 coming into contact with the ground, and thereby elevating the front end. Once the car is safely in flight, it can be controlled, raised, lowered, steered to right or left, and balanced by adjustment of the wings and of the aerocar and propeller, as hereinbefore described, all these capacities for adjustment giving a very thorough and effective means of control.

An additional mode of control and of securing balance is afforded by the means which I am now about to describe for deflecting and bending down the tips of the wings. The hand control rods 31 and 32 have downwardly projecting arms 108 and 109 near their forward and rear ends respectively, and from these arms extend wires 110 and 111 to the lower ends of the struts of the anterior and posterior truss frames of both wings. These wires pass around pulleys at the ends of the struts and thence pass to the tips of the wings. The hand rods are rotatable in their bearings and by twisting or turning them a pull may be exerted on the wires 110 and 111 suffi-

cient to bend down the tips of the wings to assist in balancing in the manner employed by birds. Only the extreme tips of the wings are thus deflected, because the struts 9 rigidly support the wing surfaces at the points where they are connected thereto.

The aerocar is designed to carry a passenger and for that purpose I provide a seat or chair 112 supported at the bottom of the U-shaped frame 48. Provision is made also for the control of the aeromobile by the passenger occupying this seat, in order that he may guide the machine to safety in case of the incapacity of the driver occupying the stand in the winged aeroplane. Accordingly I provide a bar 113, projecting down from the collar 67 within reach of the occupant of the seat 112, such arm having a transverse handle. By pushing or pulling on the bar the passenger may tilt the planes of the aerocar up or down, thereby causing the machine as a whole to respectively descend or rise, while by grasping the handle of the bar and exerting a twisting stress the aerocar may be swung to right or left, whereby to steer in either direction. Also between the winged aeroplane and aerocar is an additional seat 114 suspended from the shaft casing 2 by a collar 115, which is movable thereon to balance the weight carried by the seat. A line 116 is connected to the collar 115 and passes around pulleys in such a position as to be accessible to the driver and to the occupant of the seat 112, whereby the seat 114 and its occupant may be arbitrarily shifted to the point required by the exigencies of the situation.

Owing to the manner in which the parts of the aeromobile are associated together, it may be readily taken apart for shipment or storage in a small space, or for independent use of the different parts, and may with equal ease be reassembled. When taken off, the aerocar may be independently used as a glider for the purposes of experiment, instruction and amusement, in which case the wheel 105 and seat 112 may be removed. The winged aeroplane may also be used independently in gliding and for experimentation as to the effect produced by adjustment of the wings at different angles. It is also within my contemplation to reverse the relative arrangement of the aeroplane and aerocar, putting the latter in front and the former in the rear, and to make a corresponding reversal of the positions of the main and auxiliary propellers. Any or all of the parts may also be duplicated on a sufficiently long shaft or backbone, and thus a multiple aeroplane may be constructed according to the same principles, capable of indefinite extension as to lifting power and carrying capacity.

I propose and reserve the right, to use valvular wings of such form as to open

when the wings are raised and close when the wings are depressed or held stationary, as by such a construction the wings may be utilized for raising the apparatus in a manner similar to the flapping wing motion of birds. In making the valvular wing covering, the fabric instead of being continuous and fixedly applied to the wing frames, would be arranged in suitably stiffened strips hung at one edge of the wing frames and so connected as to swing open when a relatively downward current of air strikes them, but to be held closed while there is any upward pressure of the air on their under surfaces.

A feature of construction of the aerocar which I deem of considerable importance is that the covering of the superposed planes of the aerocar does not extend entirely from end to end, but there is an open place left in the center of each plane between the two innermost ribs, thereby the air may pass upward through the central part of the planes in case the same are tilted, without requiring to traverse the whole length of the planes before escaping.

As a material for the frame work of the aeromobile, I propose to use thin and light, but strong, steel tubing, such as is used in bicycle frames, or I may use the common U-steel. I do not desire to be limited, however, to any particular material, but reserve the right to use any other metal, or wood, in accordance with the principles known and practised at the present day. In order to save weight I propose to make the shaft casing 2 of skeleton form, having a large amount of material removed from it and having only enough material left to give it sufficient rigidity for the purposes required.

Also I propose to employ roller or ball bearings between the casing and shaft to reduce friction in the well-known manner.

I have provided for utilizing a motor of the internal combustion type, using liquid fuel, and also for water-jacketing the motor. For containing the water and liquid fuel I have arranged tanks 117 and 118 supported by the wing frames and connected respectively by pipes 119 and 120 with the motor. These tanks are preferably made with two or more compartments, each of which contains half of the liquids, and from both of which tanks the liquid fuel is simultaneously or in alternation withdrawn. This arrangement is provided in order that the balance of the aeroplane may not be disturbed by the different specific gravities of the liquids and by the consumption of one of them.

I have previously stated that the wings and aerocar may be monoplanes, and in order to illustrate this principle and also to show the feasibility of having only a single truss frame for each plane, I have provided

Figs. 11 to 16 inclusive. From these figures and particularly from the under plan view of Fig. 11 and the elevation of Fig. 12, it will be seen that each of the wings consists of a single plane, formed of side members 125, 126, and transverse ribs 127, over which the fabric to furnish the supporting surface is stretched. These planes are each supported by a single truss frame consisting, as in the multiplane type, of a longitudinal member 5, one or more struts 6, 8 and 9 and a chord 7, as before described. The planes are supported by the longitudinal members of the truss frames and are prevented from being displaced by guy wires or members 128 and 129, which are extended at a suitable number of points from the forward and rear edges of the planes to the struts.

In like manner the aerocar is made with a single plane which is suspended from the legs of the U-shaped rigid frame 48^a in a manner equivalent to that already described.

In other respects the aeromobile as a whole is substantially the same as previously described, with the exception that as shown in Fig. 12 the platform 33^a extends forward of the motor instead of in the rear thereof, and that the operator's station is therefore in front of the motor. As a consequence of this modification in arrangement, the foot holds 24^a for the operator on the short arms of the wing truss frames extend forwardly, as is also shown in Fig. 12. Many modifications in the details of construction of the flying machine as a whole other than those specifically noted may be made. That is, it is not essential that the shaft or backbone be solid, but it may be tubular if desired, and likewise the shaft casing 2 need not be a tubular casing, but it may be any sort of frame work, such for instance as a prismatic skeleton frame. The essence of the invention is found in any construction of backbone or frame having sufficient stiffness and capable of being rotated about an axis parallel to or coincident with the axis of the shaft.

It will be noted that as a result of the pivotal mode of mounting the wings, they are enabled to wave up and down and may be extended in a substantially horizontal position, whereby their horizontal wing area resisting descent of the machine is increased to the maximum, or they may be raised or waved upwardly to decrease the extent of horizontal area over which they extend when it is desired to descend, or to balance the machine. At the same time that the wings are waved upwardly, the weight of the operator is lowered so that at the same time the center of gravity of the apparatus as a whole, including the operator, is lowered, while the center of air pressure is relatively raised, and thus the distance between the center of gravity and center of

buoyancy, or, in other words, the metacentric height is varied. This affords an almost instantaneously acting mode of preserving equilibrium and stability. With the 5 wings elevated the machine is exceedingly stable, for if it should careen or tilt the wing on the descending side it would be brought toward the horizontal, thereby increasing its resistance to descent and at the 10 same time the other wing is made more nearly vertical, correspondingly decreasing its sustaining power. The upward air pressure is thus concentrated on the descending wing and the machine is automatically restored to correct balance.

15 In descending the wings will be raised so as to diminish the relatively upwardly acting air resistance, and then, when approaching the ground, they will be suddenly 20 outspread to check the descent and allow the machine to alight gently.

It is possible and easily feasible to 25 enclose the space between the planes of the wings and the planes of the aerocar in the multiplane form of the machine with gas-tight fabric which, with the fabric covering of the planes, provides spaces adapted to contain a gas lighter than air, whereby additional sustaining power may be secured.

30 It is possible also with the monoplane type to support or attach gas bags upon or to the wings. The wings when thus made to form, or to have attached thereto, gas bags are operable in the same manner as has already 35 been described, and when so constructed or provided make of the machine an improved and more manageable dirigible balloon. This I consider to be an important feature of my invention.

40 I claim,—

1. A flying machine comprising a central longitudinal member or backbone, wings pivotally mounted upon said central member and extending to either side thereof, and 45 a controlling member having a horizontal surface and a vertical surface pivoted upon said backbone, and oscillable about the axis of the backbone and also about horizontal and vertical axes.

50 2. A flying machine comprising a longitudinal backbone, wings pivoted upon said backbone and extending to either side thereof, and a controlling device mounted upon said backbone independently of said wings 55 and oscillable transversely about the axis thereof and also about a substantially horizontal axis at right angles thereto.

3. A flying machine comprising a body structure, motive and propelling mechanism 60 mounted on said structure, wings independently pivoted to said body structure on a central longitudinal axis, each having a supporting surface located wholly on one side of the axis opposite to the other wing, and 65 including also frame members extending

across the axis, links hung from the extended portions of the wing frame members, an element connected to the links of both wings, and means engaged with said element for moving the same and thereby oscillating the 70 wings.

4. A flying machine comprising a body structure, motive and propelling means mounted upon said structure, wings independently pivoted to said body structure on 75 a central longitudinal axis, each having a supporting surface located wholly on one side of the axis opposite to the other wing, and including also frame members extending across the axis, and means connected 80 with the frame members of each wing on opposite sides of the axis for so moving said wings as to bring the weights and sustaining forces of the machine in the line of propulsive thrust, and to lower the center of gravity below the center of sustaining force, for 85 inherent stability, respectively.

5. A flying machine comprising a winged aeroplane having angularly adjustable wings extending toward opposite sides of the flying machine, a driving propeller arranged to exert its thrust in a fore-and-aft direction, a backbone, and an aerocar pivotally mounted upon said backbone, said aerocar consisting of a substantially horizontal 90 plane and parallel vertical rudder planes on opposite sides of the backbone, and being adjustable about axes parallel to its respective planes.

6. A flying machine comprising a forward 100 member having supporting planes or wings, a rear member having supporting planes, a frame member connected with said members, means for altering the angle between the wings or planes of one of said members, and 105 a connection between said means and the other said member, whereby the same means may serve also for altering the angle of the planes of the other said member.

7. A flying machine comprising in combination a central longitudinal shaft, a propeller secured to said shaft, a driving motor for rotating said shaft, wings extending laterally to either side of said shaft, and pivotally mounted to oscillate about the axis 115 of the latter, means by which said wings may be so moved about this axis to adjust to any desired degree the angle between them and the vertical, and means for holding the wings at such angle.

8. A flying machine comprising a central propeller shaft, a motor, wings pivotally mounted upon said shaft and extending to either side thereof, and means connected to said wings at opposite sides of the axis 125 thereof by which an operator may apply his weight upon the wings at opposite sides of the pivotal axis thereof, for raising and depressing the wings, the wings being so related in position to said shaft as to give in- 130

herent stability when raised, and non-inherent stability when lowered, for propelled flight.

9. A flying machine comprising a pair of laterally extending wings pivotally mounted to oscillate about an axis extending in the direction of normal forward movement of the machine, means whereby the operator of the machine is enabled to transfer his weight to parts of said wings on respectively opposite sides of the pivotal axis thereof, and means whereby the operator may apply his weight to the pivotal axis of such wings to relieve the wings of such weight.
10. A flying machine comprising a pair of laterally extending independently pivoted mounted wings, means controlled by the operator for changing the angles of the wings of the pair equally and oppositely as a whole about their pivotal axis, and means for independently deflecting the tips of the wings.

11. In a flying machine a wing structure consisting of a truss frame extending transversely of the direction of normal travel of the machine, and a supporting surface having a frame-work independent of said truss frame and a covering, carried by said frame, the frame having a longitudinal member, a strut extending downwardly between the ends of such longitudinal member, and tension members passing from the ends of said longitudinal member to the lower end of said strut.

12. In a flying machine a wing structure consisting of a truss frame having a longitudinal member, a strut extending downwardly from such longitudinal member between the ends thereof, and a tension member connected to the ends of said longitudinal member and the lower end of said strut; and a supporting surface carried by said truss frame and suitably secured and braced thereto.

13. In a flying machine a wing structure consisting of two or more truss frames, each having a longitudinal member, a transverse strut, and a tension member uniting the opposite ends of said longitudinal member with a point on said strut, remote from said member; ribs extending transversely across the truss frames and secured to the longitudinal members thereof, and a fabric having an extended surface supported by said longitudinal members and ribs.

14. In a flying machine, the combination of a main shaft, wing frames crossing said shaft and pivotally connected thereto, said frames having wide supporting surfaces, links hung from the ends of said frames and connected together below said shaft, a support for the operator supported by said links, and a second support for the operator hung from said shaft independently of said links and in such relation to said first sup-

port that the weight of the operator can be readily shifted from one to the other.

15. In a flying machine a pair of pivotally connected wings extending transversely of their pivotal axis, and having short arms extending across such axis, a support for the operator suspended from the axis at a distance below the same which is a fraction of the height of the operator, and a second support for the operator connected to the short arms of said wings in such relation to said first support that the weight of the operator may readily be transferred from one to the other.

16. In a flying machine a pair of wings extending toward opposite sides of the machine and pivotally mounted to swing about an axis transverse to their length, each said wing having a short arm on the opposite side of its pivotal axis, a support for the operator connected to the short arms of said wings whereby the weight of the operator applied on said support tends to elevate the wings, elastic means normally tending to depress the wings, and a second support for the operator hung from the pivotal axes of the wings in such position that the operator may readily shift his weight from the first support, whereby said elastic means is enabled to depress the wings.

17. In a flying machine a pair of pivotally mounted wings having extended supporting surfaces, and each wing having a short arm on the opposite side of its pivotal axis from its supporting surface, foot pieces connected with the short arms of said wings, whereon the operator may stand to cause his weight to elevate the wings, and hand holds for the operator attached respectively to each wing on the opposite side of its pivot from the foot piece thereof, whereby the operator may transfer his weight to depress the wings.

18. In a flying machine a pair of pivotally connected wing frames extending to opposite sides of their pivotal support, each said wing frame having a long lever arm carrying a fabric-supporting surface and a short arm on the opposite side of its pivot, foot pieces attached to the short arms of the respective wing structures, links hung from said short arms and connected together, an operator's seat supported upon the point of connection of said links, an operator's platform suspended from the pivot of the wings and hand grips supported upon the wing structures on the opposite sides of the pivot thereof from said foot pieces, said foot pieces, seat, platform and hand grips being arranged in proximity to each other, whereby the operator is enabled conveniently to shift his weight from one to another thereof.

19. In a flying machine a pair of pivotally connected wing frames extending to opposite sides of their pivotal support, each said

- wing frame having a long lever arm carrying a fabric-supporting surface and a short arm on the opposite side of its pivot, foot pieces attached to the short arms of the respective wing structures, links hung from said short arms and connected together, an operator's seat supported upon the point of connection of said links, an operator's platform suspended from the pivot of the wings, and hand grips supported upon the wing structures on the opposite sides of the pivot thereof from said foot pieces, said foot pieces and platform being slightly below the axis of the wings, and said seat and hand grip being above such axis, and all in relatively close proximity to one another, so that the operator may easily transfer his weight from one to another.
20. In a flying machine a central longitudinal casing, a winged aeroplane supported upon said casing, a driving shaft passing longitudinally through said casing, a motor for rotating said shaft, a propeller secured upon said shaft, a guiding aerocar having substantially horizontal and vertical planes pivotally attached to said frame by both horizontal and vertical pivots, means for oscillating said aerocar about either of said pivots, and means for swinging said frame about its longitudinal axis and thereby careening said aerocar.
25. A flying machine comprising an aeroplane having laterally extending wings adjustable at varying angles of slant with respect to the vertical, and about an axis parallel to the normal line of flight of the machine, whereby to secure balance and stability, means whereby the angles of said wings may be adjusted during flight, a guiding aeroplane structure having substantially horizontal and vertical planes, and a longitudinally extending backbone to which said guiding aeroplane is pivotally connected, and upon which the latter may 30 be moved about substantially horizontal and vertical axes.
35. A flying machine, comprising a central longitudinal frame member or backbone, a winged aeroplane connected to said backbone and having a support for an operator, a guiding aeroplane structure having substantially horizontal and vertical planes pivotally mounted upon said backbone, means controlled by the operator for swinging said guiding aeroplane structure about a horizontal axis and from side to side about a vertical axis, a support for a passenger suspended from said guiding aeroplane structure, and means within reach 40 of the occupant of such support for adjusting the said aeroplane structure about either axis.
45. In a flying machine, the combination of a main winged supporting aeroplane, a guiding aeroplane separate from said sup-

porting aeroplane, a connecting frame, supports for operators independently carried by said plane and guiding plane respectively, and means accessible to and operable by each operator for shifting the 70 guiding aeroplane to change the elevation of and steer the machine as a whole.

24. In a flying machine an aerocar consisting of a U-shaped frame having substantially vertical legs, and a substantially 75 horizontal wing or supporting plane structure consisting of a separate framework and a covering arranged transversely of the legs of said frame, and between the ends thereof, and braces extending from different 80 points of said plane to the frame, above and below the plane.

25. In a flying machine a main supporting winged aeroplane, a backbone, and a gliding aerocar detachably connected to 85 said backbone and consisting of a substantially vertical U-shaped frame and a substantially horizontal plane supported by and braced to said frame, said aerocar being oscillative for guidance and control.

26. In an aeroplane structure a U-shaped frame, a substantially rectangular aeroplane frame forming a structure independent of said U-shaped frame having longitudinal members, transverse members and a fabric 95 covering, suspenders by which said aeroplane frame is hung from the legs of such U-shaped frame, and braces connected with said aeroplane frame and U-shaped frame for retaining the latter in an invariable relation to each other.

27. In an aeroplane structure the combination of a U-shaped main frame having upright legs, superposed aeroplane frames, suspension members by which said aeroplane 105 frames are hung from the legs of said main U-shaped frame, and tension braces connecting said aeroplane frames with said U-shaped frame, and with each other, for holding them in an invariable relation.

28. In an aeroplane the combination of two or more superposed planes, a single rigid frame consisting of substantially parallel side members and a connecting member, and tension members suspending said 115 planes from the side members of said frame, and bracing said planes against displacement from their proper position with respect to the frame.

29. In an aeroplane, the combination of 120 oscillatively mounted wings, with motive and propulsive mechanism, and means for raising and lowering the wings, said wings being arranged and located with respect to the propulsive mechanism so that, when lowered, the center of gravity, and center of sustaining pressure, are coincident with the line of propulsive thrust; and when raised, the center of gravity of the machine and operator is below the center of sustaining 125 130

upward pressure, whereby inherent stability is secured.

30. The combination in a winged flying machine of pivoted laterally and oppositely extended wings, a support for an operator between said wings and above the pivotal axis thereof, and a parachute frame extending above and on both sides of the operator and having a sustaining surface, said frame 10 at the sides of the operator carrying transparent steady rudder vanes.

31. A flying machine comprising a body structure, propelling mechanism, and supporting planes or wings adjustably mounted 15 on said structure with provision for being lowered to a position in which the center of sustaining pressure is in the line of propulsive thrust, and of being raised above such position.

32. A flying machine comprising a body 20 structure, propelling mechanism, and supporting planes or wings adjustably mounted on said structure with provision for being lowered to a position in which the center of sustaining pressure is in the line of propulsive thrust, and of being raised above such position, said planes also having their 25 weights so distributed with respect to the weight of the balance of the machine, that when in such lowered position, the center 30 of gravity of the entire machine is in the same line.

In testimony whereof I have affixed my signature, in presence of two witnesses.
